UNITED STATES PATENT OFFICE

ROY W. BACON, OF ADAMS, NEBRASKA

ATOMIZER

Application filed September 7, 1928. Serial No. 304,430.

This invention relates to improvements in atomizers and has for its principal object to provide a device that is particularly adapted to be used for spraying either the throat or 5 the nose with a medicament under pressure.

One of the important objects of the present invention is to provide an atomizer which is simple in construction, inexpensive, and furthermore adapted to the purposes for which 10 the same is designed.

Other objects and advantages of this invention will become apparent during the course of the following description.

In the accompanying drawings forming 15 part of this specification and in which like numerals are employed to designate like parts throughout the same:

Fig. 1 is a side elevation of the atomizer embodying my invention,

20 Fig. 2 is a top plan view thereof,

Fig. 3 is a sectional view taken approximately on the line 3—3 of Figure 2,

Fig. 4 is a sectional view taken approximately on the line 4—4 of Figure 2,

25 Fig. 5 is a vertical sectional view taken substantially on the line 5—5 of Fig. 1,

Fig. 6 is a fragmentary enlarged detail of the forward end portion of the atomizing chamber, parts being shown in section,

30 Fig. 7 is a sectional view taken substantially upon the line 7—7 of Fig. 1, looking in the direction of the arrows, and,

Fig. 8 is a forward end elevation of the atomizing chamber, the cap being removed.

35 In the drawings, wherein for the purpose of illustration is shown the preferred embodiment of my invention, the numeral 1 designates a hollow spherical medicament container or receptacle that is preferably constructed of glass, the same being formed at its top with a filling neck 2 into which is threaded the head 3.

This head 3 provides a closure cap for the filling neck and is inserted after the receptacle or container 1 has been properly filled with the fluid to be used in spraying for medicinal purposes. The head 3 is formed with a vertical bore 4 for the full length thereof and threaded in the upper end of the 40 bore is the thumb actuated valve 5, the pur-

pose of which will be presently described. The head 3 is further formed in one side with a passage 6 and has communication with the longitudinal bore 4 and attached to this side of the head for communication with the passage 6 is a hand pump of any conventional construction, the same being denoted generally by the reference character 7.

The pump is provided for placing the fluid in the receptacle or container 1 under pressure and air under pressure is admitted to the receptacle when the valve 5 is moved upwardly out of engagement with the inner end of the transverse bore 6. When the valve is positioned in the manner shown in Fig. 3, communication is cut off between the passage 6 and the bore 4.

The opposite side of the head 3 is provided with an inner passage 8 that has communication with the receptacle 1 and a gauge 9 of any conventional construction is arranged on this side of the head for communication with the passage 8 whereby the user may readily ascertain the exact amount of air pressure within the receptacle or container 1. By attaching the pump and the gauge to the opposite sides of the head 3, a unitary structure is provided.

The bottom of the spherical container 1 is provided with an outlet neck 10 from which extends a discharge pipe 11, said pipe extending horizontally. The inner end portion of the pipe is curved upwardly and is detachably secured to the outlet neck 10 by a suitable coupling shown at 12 in Figs. 1 and 3. The outer end of the horizontally disposed pipe 11 is connected to one end of the pipe 13 that extends from the inner end of the substantially oval-shaped atomizing chamber 14, which chamber is open at its forward end and a cap 15 is slidably fitted over the open forward end portion of the atomizing chamber in the manner as shown in Figs 4 and 6. The forward end of the pipe 13 is formed with a restricted liquid discharge orifice 16 with which cooperates the pointed end of a needle valve 17 that is adjustable through the central portion of the cap 15 and extends into the atomizing chamber 14 as also shown very clearly in Fig. 4. The outer end portion of

100

the needle valve 17 is enlarged and threaded as shown at 18 and the central portion of the cap 15 is formed with a conical-shaped raised portion 19 on the inner side thereof through which the threaded portion 18 extends.

An internally and externally threaded neck 20 is formed on the outer face of the central portion of the cap 15 through which the threaded portion 18 of the needle valve 17 also extends and a removable cap 21 is threaded on the neck 20. The outer end of the needle valve 17 is formed with a kerf shown at 22 to accommodate a suitable implement to facilitate turning of the needle valve in order to adjust the pointed end thereof with respect to the discharge orifice 16 whereby to regulate the flow of the fluid under pressure from the discharge pipe 11 and 13 to the atomizing chamber 14.

As clearly shown in Figs. 4 and 7, the inner end of the oval-shaped atomizing chamber 14 is formed with a series of airholes 23 so that the fluid that enters the atomizing chamber will become co-mingled with the air that enters the chamber 14 through the airholes 23.

A pair of discharge nipples 24 and 25 are associated with the cap 15 and the atomized fluid leaves the chamber 14 through these discharge nipples and when the atomizer is used for spraying the throat, the user places both nipples 24 and 25 in his mouth whereupon said nipples constitute nozzles.

When the atomizer is used for the nostrils, a flexible tube shown at 26 in the dotted lines in Fig. 1 is employed, the inner end thereof being formed with branch pipes or stems 27 and 28 that detachably engage over the nipples 24 and 25. A nozzle 29 is arranged on the outer end of the tube 26 for insertion upwardly in the nostril.

Also forming a salient part of the present invention is the spring pressed valve that normally cuts off the supply of the medicine from the chamber or receptacle 1 through the atomizing chamber 14. This valve comprises a vertically slidable stem 30 arranged for slidable movement through the intermediate portion of the pipe 13. The intermediate portion of the stem is formed with an opening 31 that is adapted to have communication with the bore of the pipe 13, it being understood of course that a portion of the pipe in which the valve stem is mounted is slightly enlarged. A push button 32 is arranged on the upper end of the stem 30, while a stop forming plate 33 is carried by the lower end of the stem. An expansible coil spring 34 encircles the upper portion of the stem and is disposed between the push button 32 and the top of the pipe 13 for normally holding the stem in its raised position so that the plate or disc 33 is held against the pipe and the opening 31 is maintained out of engagement

for communication with the bore of said pipe 13.

When in use, the push button 32 is depressed whereupon the stem 30 moves downwardly through the pipe 13 so as to bring the opening 31 into communication or registration with the bore of the pipe and in this manner, the fluid under pressure will flow from the receptacle 1 into the atomizing chamber 14 and out through the discharge nipples in the manner as heretofore described. As soon as the pressure is taken off of the push button, the spring 34 will return the valve to its normally closed position thereby cutting off further supply of the fluid under pressure to the atomizing chamber.

It will thus be seen from the foregoing description, that I have provided an atomizer that will at all times be efficient and reliable in its operation, and furthermore the parts are so constructed as to permit the same to be readily and easily assembled or disassembled whenever necessary.

While I have shown the preferred embodiment of my invention, it is to be understood that various changes in the size, shape and arrangement of parts may be resorted to without departing from the spirit or scope or sacrificing any of the advantages of the appended claims.

What I claim is:

1. In an atomizer, an atomizing chamber open at its forward end, a removable cap therefor, a liquid supply pipe having communication with the rear end of the atomizing chamber, the rear end of the atomizing chamber being provided with a series of air openings, a discharge nozzle carried by the cap for communication with the atomizing chamber, and a needle valve extending through the cap into the atomizing chamber for co-operation with the forward end of the supply pipe to regulate the flow of the liquid into the atomizing chamber.

2. In an atomizer, an atomizing chamber open at its forward end, a removable cap therefor, a liquid supply pipe having communication with the rear end of the atomizing chamber, the rear end of the atomizing chamber being provided with a series of air openings, a discharge nozzle carried by the cap for communication with the atomizing chamber, and a needle valve extending through the cap into the atomizing chamber for cooperation with the forward end of the supply pipe to regulate the flow of the liquid into the atomizing chamber, and a cut-off valve mounted in the liquid supply pipe.

3. In an atomizer, an atomizing chamber open at its forward end, a removable cap therefor, a liquid supply pipe having communication with the rear end of the atomizing chamber, the rear end of the atomizing chamber being provided with a series of air openings, a discharge nozzle carried by the cap

for communication with the atomizing chamber, and a needle valve extending through the cap into the atomizing chamber for cooperation with the forward end of the supply pipe to regulate the flow of the liquid into the atomizing chamber, and a cut-off valve mounted in the liquid supply pipe, said cut-off valve comprising a vertically slideable stem formed with an opening transversely therethrough, a plate attached to one end of the stem, a push button carried by the other end of the stem, and an expansible coil spring interposed between the push button and the top of the supply pipe for normally maintaining the stem in a raised position with the plate bearing against the bottom of the pipe and the transverse opening out of communication with the bore of the supply pipe, said opening adapted to register with the bore of the supply pipe when the push button is depressed.

In testimony whereof I affix my signature.

ROY W. BACON.
